UNITED STATES PATENT OFFICE.

THOMAS J. PORTER, OF OROVILLE, CALIFORNIA, ASSIGNOR OF ONE-THIRD TO PAT-RICK LYONS AND ONE-THIRD TO A. CLYDE MASTELLER, BOTH OF OROVILLE, CALIFORNIA.

WATER-LIFTING APPARATUS.

Application filed December 6, 1927. Serial No. 238,143.

The present invention is concerned with the provision of a unique water-elevating or pumping mechanism arranged to lift a maximum quantity of water with a minimum amount of power. An object of the invention is to provide a mechanism of this character which will not only be mechanically efficient, but which will be of simple, practical construction, rugged and durable in use, and well suited to the requirements of economical installation and inexpensive operation in any connection where water is to be elevated.

With the above noted and other objects in view, the invention consists in certain novel features of construction and combinations and arrangements of parts, as will be more fully hereinafter set forth and pointed out in the claims. The invention may be more fully understood from the following description in connection with the accompanying drawings, wherein—

Fig. 1 is a view in vertical section through a pumping apparatus embodying the present invention.

Fig. 2 is a vertical sectional detail on the staggered line 2—2 of Fig. 1.

Fig. 3 is a sectional plan view of the apparatus taken approximately on the line 3—3 of Fig. 1.

Fig. 4 is a fragmentary view generally similar to Fig. 1, but indicating the opposite extreme position of the curved oscillating pipe.

In the drawings I have used the reference numeral 10 to designate a water reservoir of any suitable character, and the numeral 11 to designate a spillway disposed well above the reservoir and into which water from the reservoir is to be pumped. Arranged within the reservoir 10 is a closed water chamber 12 into which water from the reservoir flows through inwardly opening check valves 13 (Fig. 2). An open pipe 14 communicating with the top of the chamber 12 terminates above the water line in the reservoir and prevents air from being entrapped in the chamber 12.

Arranged adjacent the reservoir is a frame 15 of any suitable design mounting split bearings 16 in which a rocker shaft 17 is journaled. An arcuate length of pipe 18 is supported on spokes 19 projecting from a hub 20 secured to the rock shaft 17. Shaft 17 is disposed exactly at the center of gravity of the pipe 18, so that the pipe is in unstable equilibrium, and but slight power will be re-

quired to oscillate it in either direction about the shaft 17.

Directly connected to the lower end of the pipe 18 is a short length of pipe 21 curved on a center struck from the shaft 17. The pipe 21 section 21 works through a stuffing box 22 in one wall of the closed chamber 12, and an outwardly opening check valve 23 controls communication between the pipes 18 and 21. As the pipe 18 is oscillated, pipe section 21 reciprocates inwardly and outwardly through the stuffing box; its two extreme positions being illustrated in Figs. 1 and 2.

The upper end of the arcuate pipe 18 moves over the end of the spillway 11 or other suitable water receptacle when this pipe has been tilted to the extreme dotted line position of Fig. 1 in order that water may be discharged from the upper end of the pipe 18 into the spillway.

Suitable mechanism is provided for imparting the necessary oscillating movement to the pipe 18 due to the balancing of the pipe 18 in unstable equilibrium, but little power is required to rock it in either direction, and the oscillating mechanism therefore requires but little power. I have illustrated in this connection a motor 25 driving a shaft 26 through belt 27. A disc 28 is mounted on the shaft 26 and one end of a pitman 29 eccentrically connected to the disc as at 30. The opposite end of the pitman is forked as at 31 to straddle the pipe 18 and is pivotally connected to one of the collars 32 which encircle pipe 18 and provide anchorages for the spokes 19.

The operation of the device is substantially as follows. Assuming the pipe 18 to be originally empty and in the position of Fig. 1, water will flow into the pipe 18 until it reaches the level of the water in the reservoir 10. The motor 25 is then started, and the pipe 18 shifted from the position of Fig. 1 to the position of Fig. 4. During the course of movement of the pipe to the position of Fig. 4, check valves 13 will open, and water be drawn into the chamber and into the pipe 21. On a reverse movement of the pipe 18 the water from the pipe 21 will enter the pipe 18 and after a few reciprocations of the pipe 18 the device will have become primed, or in other words, filled with water as illustrated in Fig. 1.

From this time on, it will be noted that as the pipe 18 is tilted to the dotted line posi-

tion of Fig. 1, water will be discharged from the upper end thereof into the spillway, and when returned to the full line position of Fig. 1, water will enter the pipe 18 through 5 the pipe 21; the checks 13 and 23 functioning in the manner above described.

It will be obvious that instead of the arcuate run of pipe illustrated, the pipe 18 might be formed of various compound curvatures 10 which would produce the same result, that is to say, permit the oscillating pipe to be mounted in unstable equilibrium for rotation about an axis located at its center of gravity. It will also be apparent that the cross sectional shape of the pipe 18 is subject to an infinite number of variations.

Obviously, various changes and alterations might be made in the general form and arrangement of the parts described without departing from the invention. Hence I do not wish to limit myself to the details set forth, 20 but shall consider myself at liberty to make such changes and alterations as fairly fall within the spirit and scope of the appended 25 claims.

I claim:

1. A water elevating apparatus comprising a curved pipe open at both ends and mounted to oscillate about a horizontal axis eccentric 30 to the major portion thereof and coincident with its own center of gravity, a water chamber having a stuffing box therein through which the lower end of the pipe reciprocates as the pipe is oscillated, one-way valve mechanism controlling the flow of water into the chamber and one-way valve mechanism controlling the flow of water from the chamber into the pipe.
2. A water elevating apparatus comprising 40 a curved pipe open at both ends and mounted to oscillate about a horizontal axis eccentric to the major portion thereof and coincident with its own center of gravity, a water reservoir, a chamber in the reservoir and having 45 a stuffing box therein through which the lower end of the pipe reciprocates as the pipe is oscillated, one-way valve mechanism controlling the flow of water from the reservoir into the chamber and one-way valve mechanism controlling the flow of water from the chamber into the pipe, and means for oscillating the pipe to alternately take water into its lower end and spill water from its upper end.
3. A water elevating apparatus comprising 55 a curved pipe open at both ends and mounted to oscillate about a horizontal axis coincident with its own center of gravity, a water reservoir, a chamber in the reservoir and communicating with the same and having 60 a stuffing box therein through which the

lower end of the pipe reciprocates as the pipe is oscillated, one-way valve mechanism controlling the flow of water into the chamber and one-way valve mechanism controlling the flow of water from the chamber into the pipe, and means for oscillating the pipe to alternately take water into its lower end and spill water from its upper end, the lower portion of the pipe which works through the stuffing box of the chamber being curved on a center different from that of the pipe.

4. A water elevating apparatus comprising a curved pipe open at both ends and mounted to oscillate about a horizontal eccentric axis eccentric to the major portion thereof and coincident with its own center of gravity, said pipe having its lower end curved on a center coincident with the eccentric axis, a reservoir, a water chamber in the reservoir and communicating with the same, said chamber having a stuffing box therein through which the lower end of the pipe reciprocates as the pipe is oscillated, one-way valve mechanism controlling the flow of water into the chamber and one-way valve mechanism controlling the flow of water from the chamber into the pipe, and means for oscillating the pipe to alternately take water into its lower end and spill water from its upper end.

5. A water lifting apparatus, comprising a reservoir, a water chamber in the reservoir and having a valved connection therewith, said chamber having a stuffing box in one side with a curved pipe having the lower end curved on a center different from that of the body of the pipe, a valve in the pipe a short distance from its lower end, a support at the side of the chamber having the stuffing box, means for pivotally mounting the pipe on the support, with its lower end projecting through the stuffing box of the chamber, and means for oscillating said pipe.

6. A water lifting apparatus, comprising a reservoir, a water chamber in the reservoir and having a valved connection therewith, said chamber having a stuffing box in one side, a support at the side of the chamber having the stuffing box, a rock shaft mounted on the support and provided with a hub having spokes of unequal length, an open ended curved pipe secured to said spokes and having its lower end curved on a center coincident with the rock shaft and projecting through the stuffing box of the chamber, a valve in the pipe a short distance from its lower end, and means connected with the tube for oscillating it.

Signed at Oroville in the county of Butte and State of California this 28th day of November A. D. 1927.

THOMAS J. PORTER,
